ARCH SUPPORTER

Luigi Pignanelli, Tacoma, Wash.

Application October 15, 1930. Serial No. 488,796

9 Claims. (Cl. 36—71)

This invention relates to arch-supporters for shoes, and more particularly is an improvement over devices illustrated and described in my co-pending United States application for patent, filed February 26, 1929, Serial No. 342,869, for which Letters Patent 1,844,017 issued Feb. 9, 1932.

In such prior application, I have particularly illustrated and described in detail the development of a shoe conformed to present a transverse ridge peculiarly disposed in a manner such that the astragalus bone of a wearer's foot is supported without affecting either the freedom of the heel bone, or the scaphoid and tarsal structure constituting the instep and toes.

15 The distinction is particularly set forth in such construction of a support peculiar to the astragalus bone as against the conventional "arch supporters" heretofore utilized, such latter being conformed in a convex configuration emigrating adjacent the metatarsal bones and terminating in proximity of the rear of the heel.

Such constructions afford but temporary relief and culminate in an ossified condition of the bones due to the cramping of the bone structure 25 of the foot.

The present invention, as with my prior application, is conceived to the end of allowing a freedom of heel and tarsal bones by affording a substantial rocker activity of the same about an 30 astragalus support. Recognition being taken of the fact that the operation of walking consists in the successive steps of initially coming down on the heel and centralizing the weight of the body directly over the arch, with a subsequent release and a tread to the ball of the foot as the succeeding step is taken, the primary object of the 35 present invention over my prior application is the provision of an insertable arch support embodying a yielding heel rest in cushioning the initial impact to the ground.

A further object is the provision, in insertable arch supporters of the character described, of 40 means for securely attaching the same to the upper of the shoe, in a manner such as to prevent shifting or creeping responsive to walking operations.

With the foregoing and further objects and advantages in view, such as will become apparent throughout the course of the following detailed 45 description and claims, the invention consists in the novel construction, adaptation and combination of parts hereinafter described and claimed.

In the drawing,—

50 Figure 1 is an underneath plan indicating the preferred embodiment of the present invention.

Fig. 2 is a longitudinal vertical section taken through a portion of a shoe, the present invention, indicated in side elevation, being applied therein, said view exemplifying by dash lines the 60 contour of the ankle and foot indicating the bone formation thereof as applied to the shoe and arch supporter.

Fig. 3 is a transverse vertical section taken to a reduced scale of the arch supporter removed, 65 said section taken on line 3—3 of Fig. 1, with the exception that the attachment strip of the same is shown in upright position as applied to the shoe upper.

Reference being had to Fig. 2, representing 70 therein the bone contour of a human foot, the numeral 5 indicates the astragalus disposed in the approximate vertical plane of the body and supporting the same through the tibia 6. 7 represents the os calcis, 8 the scaphoid and 9, the 75 tarsal or instep structure.

More particularly referring thereto, the os calcis or heel bone is normally disposed at an elevation below that of the scaphoid 8, being spaced therefrom at its inner side to provide a recess 10 within which the fleshy part of the underfoot 80 extends, said recess progressively increasing from the outer edge of the foot.

According to the present invention, I provide 85 an insertable insole member, such as generally represented by 11, the bearing portion thereof on the sole 12 of the shoe proper being stamped from a single piece of leather or other suitable material and pressed to provide a plane faced heel 13 jogged upwardly at its forward end and affording a wall 15 disposed at an angularity of 90 approximately thirty degrees from the vertical.

Said wall, moreover, terminates in a shoulder 95 or ridge portion 16 extending transversely of the insert, gradually diminishing from the inner to a point adjacent the outer side, whereat the same merges to the approximate upper plane of the heel. Said ridge, having a relatively small radius, is comparatively sharp, and constitutes in its projection upwardly to the astragalus and tibia 100 bones, a fulcrum affording rocker activity and extreme flexibility to the os calcis and the tarsal structure of the bone.

Said particular and advantageous configuration of the insert is suitably retained through 105 the medium of a metal brace 17 rigidly secured, as by shoe nails, to the underneath face and suitably conformed such as to have its upper supporting or platform face 18 terminate in relative proximity to the ridge, the fore portion 19 of insole 11 being beveled therebeyond to merge 110

with the built-in ball portion 12¹ of the shoe sole 12.

Yieldably elevating the heel bone 7, the invention further provides a cushion of sponge rubber, or other suitable material, such as 21 conformed to taper from the inner to the outer side and arranged for interposition above said heel portion 13 and beneath a superposed strip 22 cementitiously or otherwise united about the outer edge 23 and transversely of the fore portion of ridge 16. Said cushion insert is or may be cemented to the face of heel portion 13 and the strip 22.

Projecting laterally from said portion 19, I further provide a wing 24 disposed such as to accommodate a turn-up of the same within the instep of the shoe upper, said wing being adapted to be sewed thereto about its horizontal and vertical edges in the prevention of shifting or creeping.

The construction is believed evident from the foregoing. While I have herein described and illustrated the preferred embodiment, it is to be noted however, that I do not particularly confine myself thereto except as by the scope of the hereto annexed claims.

What I claim, is,—

1. In an insertable insole for a shoe formed to provide in its rear portion a substantially plane face adapted to be disposed in the heel portion of the shoe, the front wall of said heel portion extending substantially vertically upwardly to a transverse ridge from which the fore portion projects forwardly to the ball of the shoe, the apex of said ridge forming a relatively sharp angle serving to wedge into the fleshy part of the underfoot below the astragalus bone, said ridge sloping downwardly from the inner to the outer edge to merge at the latter with the approximate plane of said rear portion, a sponge cushion superposed over said rear portion to act as a rest for the heel of the foot, said cushion tapering from a plane relatively in alignment with the inner edge of the ridge to a feather edge on its outer side.

2. In a device as defined in claim 1, wherein the front wall, transverse ridge, and forward platform of said insertable insole are retained by a metal brace secured to the underface thereof and approximating the contour of the same.

3. In apparatus as defined in claim 1, wherein said insole is conformed to present a wing projecting laterally of the forward platform, said wing being adapted to a turn-up within the instep portion of the shoe upper for securing said wing to the same.

4. In an insole for a shoe formed to provide a plane surface in its rear portion seating within the heel cavity of the shoe, said heel surface being turned up at its forward extremity to form

a relatively sharp transverse ridge, progressing therefrom as a platform beneath the instep of a wearer's foot, said ridge sloping downwardly from the inner to the outer edge and adapted to project within the fleshy part of a wearer's foot below the astragalus bone, a cushion superposed over said rear plane surface and tapering from the inside to a substantial feather-edge on its outer side.

5. An insole for a shoe formed to provide in its rear portion a cushion for the heel of the wearer's foot, and at the fore extremity of said cushion, a transverse ridge having a relatively sharp apex arranged to wedge within the fleshy part of the foot below the astragalus bone, said cushion and ridge sloping downwardly from the inner to the outer side of the shoe.

6. In an insertable arch supporter for a shoe, said supporter being conformed to present a ridge projecting upwardly to have the apex thereof in substantial vertical alignment with a center line taken through the tibia and astragalus bones of a wearer's foot, said supporter projecting forwardly from said ridge as a platform adapted to support the instep portion of the wearer's foot, a flexible wing extending laterally of said platform and adapted to be turned up and secured alongside the interior of the shoe upper in preventing shifting of said supporter within the shoe.

7. In an insertable arch supporter for a shoe, said supporter being conformed to present a ridge projecting upwardly to have the apex thereof in substantial vertical alignment with a center line taken through the tibia and astragalus bones of a wearer's foot, said supporter projecting forwardly from said ridge as a platform adapted to support the instep portion of the wearer's foot, means for securing said supporter to the shoe to prevent shifting of the same therein.

8. In an insertable arch supporter for a shoe, said supporter formed to provide a transverse ridge disposed below the astragalus bone of a wearer's foot, a flexible wing extending laterally of said supporter and adapted to be turned up for securing alongside the interior of the shoe upper to prevent shifting of said supporter within the shoe.

9. In an insertable arch supporter for a shoe including a heel cushion, said supporter formed to provide an abutment to the heel bone of a wearer's foot forwardly of the heel portion of the shoe to prevent creeping of said heel bone towards the fore portion of the shoe, means comprising a flexible wing extending laterally of said supporter and adapted for securing with the shoe to prevent shifting of the supporter in the shoe.

LUIGI PIGNANELLI. 135
